UNITED STATES PATENT OFFICE.

PHILIP J. DUERR, OF BUFFALO, NEW YORK.

DESIGN FOR A CHAIN.

SPECIFICATION forming part of Design No. 26,667, dated February 23, 1897.

Application filed January 15, 1897. Serial No. 619,373. Term of patent 7 years.

To all whom it may concern:

Be it known that I, PHILIP J. DUERR, a citizen of the United States, residing at Buffalo, in the county of Erie and State of New York, 5 have invented and produced a new and original Design for Chains, of which the following is a specification, reference being had to the accompanying drawings, forming a part thereof.

10 This invention relates to a design for ornamental chains, such as watch-chains.

In the accompanying drawings, Figure 1 is a perspective view of a chain embodying my design, and Fig. 2 an enlarged elevation 15 thereof.

15 The leading feature of my design consists of a chain composed of solid members having the form of tablets or plates and interposed links or flexible connections arranged 20 in pairs at or near the side edges of the solid members and converging outwardly or toward said side edges.

25 A represents the solid members of the chain, consisting of tablets or plates substantially oblong in form, the tablets or plates being represented as truncated or chamfered

at the corners in the chain shown in the drawings. These tablets may be made of any ornamental stone, such as onyx, opaline, or lapis lazuli, or of any suitable artificial 30 stone.

b represents the links arranged near the side edges of the solid members A and projecting beyond the opposing edges thereof, and c are loops which connect the links of 35 adjacent solid members. The links of each pair incline or converge toward the loop with which they are enchain'd, and, as shown in the drawings, the links have ornamental inner ends. The loops have pointed or V- 40 shaped ends, and across the middle of each loop extends a bar c'.

What I claim is—

45 The design for a chain, substantially as herein shown and described.

Witness my hand this 29th day of December, 1896.

PHILIP J. DUERR.
